FRANK W. CAUGHLING, OF TOLEDO, OHIO, ASSIGNOR TO THE NATIONAL RAILWAY EQUIPMENT COMPANY, OF TOLEDO, OHIO, A CORPORATION OF OHIO.

DUST-GUARD.

1,137,120.

Specification of Letters Patent.

Patented Apr. 27, 1915.

Application filed April 5, 1913. Serial No. 759,180.

To all whom it may concern:

Be it known that I, FRANK W. CAUGHLING, a citizen of the United States, and a resident of Toledo, in the county of Lucas and State of Ohio, have invented a certain new and useful Dust-Guard; and I do hereby declare the following to be a full, clear, and exact description of the invention, such as will enable others skilled in the art to 5 which it appertains to make and use the same, reference being had to the accompanying drawings, and to the characters of reference marked thereon, which form a part of this specification.

15 This invention relates particularly to dust-guards for journal boxes, but is not restricted to such use, as it may be used in any connection for which it may be adapted or appropriate.

20 The object of my invention is the provision of an improved dust-guard of this character, which is simple and inexpensive to manufacture, light, durable and strong in its construction, and adapted to fit closely 25 within the socket provided therefor in the journal box to effectually prevent dust and dirt from entering such box through the journal-receiving opening therein, and to prevent an escape of lubricating matter 30 from within the journal-box.

A further object of my invention is the provision of a dust-guard of this character, which comprises a minimum of parts in its construction, and which has its holder or 35 body member provided with opposed yielding bearing portions which are intended to coact with the side walls of a journal box receiving socket to frictionally retain the body member in snug position therein and 40 to form close joints between the contacting marginal portions of the members and the socket walls, whereby to enhance the efficiency and practicability of devices of this class.

45 A further object of my invention is the provision of a dust-guard of this kind, the collar or floating part of which is not carried by the journal, but on the contrary is held in suspension by the opposing frictional pressure of the sides of the holder member thereagainst so that such part does 50 not have bearing contact with the journal except in following the vibratory or floating movements of the journal, thus reducing

wear and friction between such parts to a minimum, and materially enhancing the efficiency of the dust-guard.

A further object of my invention is the provision, in combination with a holder member adapted to be mounted within the dust-guard receiving chamber of a journal box, of a journal receiving collar of pressed or vulcanized fiber mounted for vibratory movements within a portion of said holder member, it being found that a journal collar of such construction will last indefinitely and stand the strains and wrenching stresses to which collars of this character are subjected in a more efficient manner than the forms of collars heretofore used for such purpose.

The invention is fully described in the following specification, and while in its broader aspect, it is capable of embodiment in numerous forms, a preferred embodiment thereof is illustrated in the accompanying drawings, in which—

Figure 1 is a side elevation of a journal box and journal therein equipped with my invention, with portions in section. Fig. 2 is a side elevation of a dust-guard embodying the invention with a part broken away. Fig. 3 is an enlarged cross-section on the line $x-x$ in Fig. 2, and Fig. 4 is an edge elevation of the dust-guard.

Referring to the drawings, 1 designates a journal box of the customary or any suitable construction having a journal receiving opening 2 in its inner end and a guard receiving socket or chamber 3 in such side in intersecting relation to the opening 2, and 4 a journal projecting through said opening into the journal box. The opening 2 is of greater diameter than the journal to permit the journal to have limited floating or vibratory movements therein.

The dust-guard comprising my invention is intended to be inserted into the socket 3 of the journal box, as is well understood in the art, and consists of a retainer or holder member, having a chamber 5 therein, and a collar member 6, which is mounted for limited floating or gyratory movements within the chamber 5 and is intended to fit quite closely around the journal 4 but free from bearing or frictional contact therewith. The holder member has a centrally disposed opening 7 through its chambered

portion for the journal 4 to project through, said opening being larger than the opening of the collar 6 to permit a limited vibratory or floating movement of the journal therein, 5 the opening 7 being preferably substantially the size of the journal box opening 2 and in axial register therewith when the dust-guard is mounted in proper position within the socket 3.

10 The collar 6 is smaller in size than the chamber 5 of the holder member to enable the collar to have limited gyratory movements therein transversely of its opening axis, and the outer edges of the collar and chamber are preferably substantially rectangular in form or of some suitable shape adapted to prevent a complete rotation of the collar within the chamber. The collar 6 is of a thickness to adapt it to snugly fit 15 between the side walls of the chamber 5 for frictional coaction therewith, whereby the collar is yieldingly held by the holder in any position in which it may be moved by the vibratory action of the journal, thus preventing any binding action of the collar on 20 the journal and reducing to a minimum the wear incident to the coacting surfaces of the collar and journal. It is preferable to make the collar 6 of pressed fiber, but it is to be understood that I do not restrict myself to 25 the use of any particular material in the making of the collar or any of the other parts of the dust-guard.

30 The holder member, comprises, in the present instance, two reversely formed duplicate side members 8-8, which are stamped, drawn or otherwise suitably formed from sheet metal or any other material adapted for the purpose. Each of 35 these side parts has its central portion drawn outwardly, as at 9, to coöperate with the corresponding portion of the other side to form the collar receiving chamber 5, the opposing portions 9 being preferably parallel and suitably spaced to permit the vibratory movements of the collar 6 therein transversely of its axis. The normal width of 40 the chamber 5 is slightly less than the width of the collar 6 to cause the opposing walls 45 of the chamber 5 to yieldingly grip the collar 6, whereby to compensate for wear between the coacting faces of the collar and chamber walls and to maintain the frictional coaction of such parts during long periods 50 of use. The side members 8-8 abut around the outer marginal edge of the chamber 5 and are riveted, welded, or otherwise suitably secured together close to the outer edge 55 of the chamber, as indicated at points 10 in Fig. 2. The members 8 extend outward from their points of fastening, or from adjacent to the marginal edge of the chamber 5, in slightly divergent yieldingly-spaced relation, and have their outer edge or rim 60 portions tapered or curved laterally in more

abrupt form, as indicated at 11, to provide a marginal edge frame or laterally broadened rim portion for the holder. The side edges of the rim portion 11 are disposed without the planes of the chamber sides 9 70 so that when the dust-guard is inserted into the journal box socket 3 the outer edges of the tapered marginal portions 11 coact with the opposing sides of the socket 3 to yieldingly space the chambered portion of the 75 holder from the socket sides, as indicated in Fig. 1. The normal width of the marginal edge or rim portion of the holder is slightly greater than the width of the socket 3 so that such portions of the holder are sprung 80 inwardly to a greater or less extent by the socket walls when inserted therein, thus providing a double dust-tight joint around the edge of the holder member. It is evident that this construction not only enables dust-guards of one side to be snugly fitted into journal box sockets of slightly varying sizes, but also serves to effectually prevent the passage of dust between the edge portions 85 of the holder member and the coacting side 90 walls of the socket.

A further advantage is incident to this construction of guard, in that the spacing of the sides 9-9 of the chamber 5 of the holder member from the sides of the socket 95 3 and the yieldingly carrying of such side portions by the outer edges or rim portion of the holder member permits the chambered portion of the holder and collar 6 to laterally yield under twisting or wrenching 100 stresses of a journal, thus very materially lessening, if not entirely preventing, the breakage which occurs in dust-guards from the twisting or wrenching action of a journal relative to the journal-box. Such construction also prevents the sides 9-9 from 105 becoming worn through by contact with the rough walls of the journal box socket 3.

It is evident that my improved dust-guard is simple and inexpensive in its construction, 110 and comprises only three parts—the collar 6, and the two side members 8-8 of the chamber—two of such parts being duplicates and of such a nature as to enable them to be rapidly stamped, drawn, or otherwise 115 suitably formed from sheet metal or other suitable material for such purpose; and also that the yieldingly spacing of the outer marginal edge portions of the holder provides a simple means for snugly retaining a 120 dust-guard within a journal box socket in a manner to prevent rattling and to effectually prevent the passage of dust and dirt around said guard and into the journal box.

I wish it understood that my invention is 125 not limited to any specific construction or arrangement of the parts except in so far as such limitations are specified in the claims.

Having thus described my invention, what 130

I claim as new, and desire to secure by Letters Patent, is,—

1. In a dust-guard, a collar holder having a centrally disposed collar-holding portion provided with opposed side walls, and also having a surrounding rim portion and a portion intermediate said collar-holding and rim portions which is transversely restricted relative thereto, and a journal encircling collar mounted in said collar-holding portion for movements relative thereto.
2. In a dust-guard, a collar-holder having opposing side members provided with registering journal receiving openings and secured together in abutting relation with their inner edge portions spaced apart to form a collar-receiving chamber within the points of secured of said members and with the rim portion of one member flared outwardly to project transversely beyond the adjacent side plane of the chambered portion, and a journal-collar mounted for radial movements in said chamber and being frictionally held by the side walls thereof.
3. In a dust-guard, a holder member comprising two plates having centrally disposed openings and secured together with said openings in register and with portions in side abutting relation entirely around said openings, the inner edge portions of the plates being spaced in parallel relation to form a collar-receiving chamber around said openings, and one of said plates having an outwardly flaring outer edge portion projecting transversely beyond the adjacent side plane of said chamber.
4. In a dust-guard of the class described, a holder member comprising a plurality of parts secured together to form a centrally-disposed collar-receiving chamber, and also to form a rim portion surrounding said chamber, which rim portion is composed of opposing members which are yieldingly spaced relative to the collar-receiving chamber.
5. In a dust-guard of the class described, a holder member of sheet metal having a centrally-disposed portion forming a collar-holding chamber, and also having a rim portion laterally yieldable relative to the chambered portion projecting outwardly from said chamber portion with its outer edge portion extended laterally beyond the adjacent side of said chamber portion and entirely surrounding the same.
6. In a dust-guard of the class described, a holder member comprising a pair of duplicate sheet-metal side portions secured together and coöperating to form both a centrally disposed collar-holding chamber and yieldingly spaced divergent rim members which rim members project laterally beyond the side planes of the collar-holding chamber and surround said chamber.
7. A three piece dust-guard of the class described comprising a collar-holding member composed of two sheet-metal plates having registering journal-receiving openings in their central portions and secured together between their inner and outer edges with their inner edge portions spaced apart in parallel relation to form a collar-receiving chamber and their outer edges divergently spaced and relatively yieldable to permit a compression thereof, and a journal-receiving collar mounted at its outer edge portion within the inner chamber of said holder for gyratory movements therein.
8. The combination with a journal box having a dust-guard receiving chamber provided with opposing side walls, of a dust-guard mounted in said chamber and having opposing side members provided with registering journal receiving openings, said members coöperating at their inner edge portions to form a collar receiving recess and being secured together without said recess, one of said side members having its outer edge portion projecting laterally from the dust-guard over and beyond the respective side wall of the recessed portion of the dust-guard to abut at its outer edge against one side wall of the dust-guard receiving chamber to protect the wall of said recessed portion from injury, and means carried by the dust-guard for coacting with the other side wall of the dust-guard receiving chamber to urge said laterally projecting edge portion against the opposing wall, and a journal encircling collar mounted for gyratory movements in said recess.
9. In a dust-guard, a collar holder having opposing side members of sheet metal provided with registering journal receiving openings, said members being secured together intermediate their inner and outer edges in side abutting relation with said openings in register and each member having its inner edge portion outwardly offset whereby they coöperate to form a collar receiving chamber which is open at its inner edge only, and one member having its outer edge flared outwardly over and beyond the inner edge offset portion thereof to protect said offset portion from injury, means for coacting with one wall of a dust-guard receiving socket to urge said flared edge against the opposing wall of the socket, and a journal-receiving collar mounted for gyratory movements in said collar receiving chamber.
10. In combination, a journal box having a journal receiving opening in an end thereof and a chamber which intersects said opening at right angles thereto, a holder removably mounted in said chamber and having an opening therethrough in register with the opening in the journal box and provide interiorly with a collar receiving chamber intersecting said holder opening, a journal

projected through said openings for transverse movements therein, a vulcanized fiber collar encircling the journal in loose non-frictional contact therewith and having its outer portion working in said holder chamber with its sides in opposed sliding frictional contact with the side walls of the holder whereby the collar is permitted to have movements in said holder and to be frictionally suspended in any position relative thereto in which it may be moved by the journal relative to the holder.

11. A dust-guard comprising a holder member having a collar receiving chamber, the walls of which are yieldable, and a journal encircling collar disposed in said chamber for gyratory movements therein, the collar being held in suspension by the spring action of the chamber walls thereon.

12. A dust-guard comprising a holder member having a journal receiving opening and a collar receiving recess surrounding said opening and open thereto, and a journal encircling collar of hard material mounted for gyratory movements in said recess, the walls of said recess co-operating to springingly grip the collar therebetween to frictionally hold it in suspension in any position to which it may be moved relative to the holder and to compensate for wear.

13. A dust-guard comprising a holder

member having a journal receiving opening and a collar receiving recess surrounding said opening and open thereto, and a journal encircling collar of pressed fiber mounted for gyratory movements in said recess, the walls of said recess co-operating to springingly grip the collar therebetween to frictionally hold it in suspension in any position to which it may be moved relative to the holder and to compensate for wear.

14. A dust-guard comprising a holder having connected side members of sheet metal, said members having registering journal receiving openings and being spaced apart immediately around said openings to form a surrounding recess, the walls of the recess being of a resilient nature, and a journal encircling collar of pressed fiber mounted for gyratory movements in said recess and held in yielding suspension in any position to which it may be moved relative to the holder by the resilient frictional coaction of the recess walls thereagainst.

In testimony whereof, I have hereunto signed my name to this specification in the presence of two subscribing witnesses.

FRANK W. CAUGHLING.
